TRANSFERRED ARM FOR WEFT
REPLENISHING LOOMS

Francesco J. Pusateri, Worcester, Mass., assignor
to Crompton & Knowles Loom Works, Worcester,
Mass., a corporation of Massachusetts

Application November 10, 1950, Serial No. 195,115

6 Claims. (Cl. 139—244)

1

This invention relates to improvements in weft replenishing looms and it is the general object of the invention to provide a bobbin transfer arm which can be adjusted for use with bobbins of different lengths.

Weft replenishing looms ordinarily employ a magazine in which are stored reserve bobbins which are transferred one by one into a shuttle when its supply of weft becomes exhausted. Some looms operate with comparatively short shuttles which carry short bobbins while other looms operate with larger shuttles carrying longer bobbins. The reserve bobbins are ordinarily made with a butt and have wound thereon a supply or package of weft which lies between the butt and the bobbin tip. In order to effect proper transfer it is desirable that the tip of the bobbin be prevented from moving upwardly at the time the butt of the bobbin is inserted into the spring jaw or clip of the shuttle being replenished. It is an important object of the present invention to provide a transfer arm with a bobbin tip engaging foot or the like which can be adjusted along the length of the transfer arm for use with bobbins of different lengths and be effective in all of its adjusted positions to prevent upward movement of the tip of a bobbin being transferred.

A transfer arm which has gone into general use in connection with a well-known type of loom has a bobbin butt engaging foot and a second foot joined to it by webs and spaced from it in the direction of the length of the bobbin. Such transfer arm is generally made for use with short bobbins. It is an important object of the present invention to provide an auxiliary or third foot which can be adjusted to occupy different distances from the aforesaid second foot and thus be adapted for use with longer bobbins.

In order that the auxiliary or third foot may be readily adjusted it is a further object of the invention to employ a screw threaded member which can turn with respect to the auxiliary foot to move the latter toward or from the main part of the transfer arm, together with a guide member, such as a rod, spaced laterally from the screw and slidable within the transfer arm. The screw and guide members are parallel and afford support for the auxiliary foot at two points spaced along its length to hold it firmly in position with respect to the remainder of the transfer arm.

With these and other objects in view which will appear as the description proceeds, the invention resides in the combination and arrange-

2

ment of parts hereinafter described and set forth.

In the accompanying drawings, wherein a convenient embodiment of the invention is set forth,

Fig. 1 is a side elevation of part of a weft replenishing loom equipped with a transfer arm made according to the present invention, the lay, shuttle, and shuttle box being shown in cross section,

Fig. 2 is an enlarged front elevation looking in the direction of arrow 2, Fig. 1, of that part of the transfer arm which extends over the bobbins to be transferred,

Figs. 3 and 4 are enlarged longitudinal sections on lines 3—3 and 4—4, respectively, Fig. 2,

Fig. 5 is an enlarged vertical section on line 5—5, Fig. 2, taken transversely of the guide member of the auxiliary foot,

Fig. 6 is an enlarged vertical section on line 6—6, Fig. 2,

Fig. 7 is a view similar to Fig. 2, but showing the transfer arm adjusted for cooperation with a longer bobbin,

Fig. 8 is an enlarged detailed vertical section on line 8—8, Fig. 4, and

Fig. 9 is a diagrammatic view showing the screw threaded member and the auxiliary foot prior to insertion of the spring washer which assists in preventing endwise movement of the screw member with respect to the auxiliary foot.

Referring to Figs. 1 and 2, the loom frame 1 supports a reserve bobbin magazine M which in the present instance carries front and back stacks 2 and 3 of reserve bobbins B₁ and B₂ which move by gravity to the bottoms of their respective stacks. The magazine is pivoted about an axis 4 and can be rocked so that the lowest bobbin of either stack can be located in transfer position. The lay 5 is provided with a shuttle box 6 to receive the shuttle S containing a bobbin B. The lay is formed with a slot 7 under the box to permit downward passage of the bobbin B when it is expelled from the shuttle S incident to a weft replenishing operation.

The magazine has a transfer arm or hammer 10 pivoted thereto at 11 and having a rearwardly extending part 12 and a laterally extending part designated generally at 13, see Fig. 2. The part 13 includes a vertical foot 14 for cooperation with the butt 15 of a bobbin in transfer position.

As viewed in Fig. 2 top and bottom webs 16 and 17, respectively, lead from the right of the foot 14 to a second vertical foot 18 preferably integral with the webs. The transfer arm 12 is provided with a latch 19 normally in

a down idle position shown in Fig. 1 but capable of being raised into the path of the bunter 21 on the lay to cause rocking of the transerrer arm in a clockwise direction as viewed in Fig. 1 due to forward movement of the lay, to the left in Fig. 1, when a replenishing operation occurs.

The magazine has an inner plate 22 to guide the butts 15 of the reserve bobbins, and has also an outer or tip guiding plate 23 to guide the small or tip ends 24 of the bobbins as they move downwardly in their stacks.

The matter thus far described is of common construction and of itself forms no part of the present invention except as noted hereinafter.

An auxiliary or third foot 25 as shown in Fig. 2 has secured thereto a guide member 26 having a preferably smooth surface to fit into a bore 27 drilled in the top web 16. A set screw 28 tapped into the top of web 16 is provided for holding the guide member 26 in longitudinally adjusted position with respect to the web 16. The auxiliary foot 25 may be secured to its guide member 26 in any approved manner, as by welding or silver soldering.

Located below the guide member 26 is an adjusting screw member 30 which is screw threaded into a tapped bore 31 in the lower web 17. A lock nut 32 holds the longitudinal adjustment of the adjusting screw member 30 with respect to the second foot 18.

The outer or right end of the screw member 30 as viewed in Fig. 2 is formed integrally with a stop 35 preferably of a shape adapting it for turning by a wrench. For this purpose the stop may be formed as a nut such as that shown at 32. The stop 35 is adapted for engagement with the left side of the auxiliary foot 25 as viewed in Fig. 2. The screw member has a shank 36 which extends through a smooth bore 37 extending through the bottom of the auxiliary foot 25, and the outer end of the screw member projects beyond the auxiliary foot as at 38 and is provided with a slot 39, see Fig. 9, to receive a spring washer 40, see Fig. 8. This washer fits into the groove 39 and together with the stop 35 prevents substantial end motion of the screw member 30 with respect to the auxiliary foot 25.

The screw member by reason of the construction shown more particularly in Figs. 8 and 9 can turn with respect to the bottom of the auxiliary foot 25 to be moved along the screw threaded bore 31 in the web 17.

As shown in Fig. 2 the auxiliary foot is relatively close to the second foot 18 to adapt it for use with a comparatively short bobbin B1 such as is used with the magazine shown. If the transerrer arm is to be used with a different magazine adapted for use with longer bobbins, such as shown at B3 in Fig. 7, the set screw 28 and lock nut 32 will be loosened, after which the screw member 30 can be turned in the web 17 by application of a wrench to the stop 35. The screw will be turned in the direction to move the auxiliary foot away from the second foot 18 until it occupies some such position as shown in Fig. 7. During this adjustment the guide member 26 slides outwardly with respect to the smooth bore 27 and when the adjustment is attained the set screw 28 and the lock nut 32 will be tightened to hold the adjustment. During this adjustment the screw turns with respect to the lower end of the auxiliary foot 25, as will be understood from Fig. 9.

From the foregoing it will be seen that the in-

vention sets forth a simple form of transerrer arm adaptable for use with bobbins of different lengths. The previously mentioned first and second feet and webs integral with them may be considered as the main part of the transerrer arm on which the auxiliary or idle foot 25 is mounted for adjustment toward and from said main part so that the auxiliary foot can engage the tips of bobbins of different lengths. It may not be necessary in all instances, however, to use the second foot. The screw member 30 can be adjusted with respect to the main part of the transerrer arm and when so adjusted causes the auxiliary foot to move with it due to the cooperation of the stop 35 and the washer 40. During this adjustment the guide member 26 slides along the bore 27. When the members 26 and 30 are tightened in position by the set screw 28 and lock nut 32, respectively, they reinforce each other and the auxiliary foot has support at two different points along its length to hold it in position against relative motion with respect to the main part of the transerrer arm. The spring washer 40 can be readily removed if it should become necessary to replace the auxiliary foot.

Having thus described the invention it will be seen that changes and modifications of the foregoing specific disclosure may be made without departing from the spirit and scope of the invention.

What is claimed as new is:

1. In a transerrer arm for a reserve bobbin having a mass of weft between the butt and top thereof, a foot on the arm to engage the butt end of the bobbin, a second foot on the transerrer arm for engagement with the weft on the bobbin, an auxiliary foot for engagement with the tip end of the bobbin, adjusting means connecting the second and auxiliary feet to vary the distance therebetween, and guide means spaced from the adjusting means slidably relatively to the second foot and cooperating with the adjusting means to support the auxiliary foot.

2. In a transerrer arm for a reserve bobbin having a butt and a tip, a foot on the transerrer arm to engage the butt of the bobbin, another foot on the transerrer arm to engage the tip end of the bobbin, adjusting means operatively connecting the two feet effective to vary the distance between said feet, and guide means on said other foot spaced from the adjusting means slidably on the transerrer arm and reinforcing said other foot for all adjusted positions of the latter relative to the transerrer arm.

3. In a transerrer arm for a reserve bobbin having a butt and a tip, a foot on the transerrer arm to engage the butt of the bobbin, another foot to engage the tip end of the bobbin, a screw member rotatable on said other foot held against endwise movement relative to the latter foot and screw threaded into the transerrer arm, and a guide member secured to the second foot parallel to and spaced from the screw member and slidable relatively to the transerrer arm.

4. In a transerrer arm for a reserve bobbin having a butt and a tip, a foot on the transerrer arm to engage the butt of the bobbin, another foot to engage the tip end of the bobbin, a screw member rotatable on said other foot and having a stop to engage one side of said other foot, means on the screw member engaging the opposite side of said other foot cooperating with the stop to prevent endwise movement of the screw member relative to said other foot, said screw member

being screw threaded into the transerrer arm, and a guide member moving with said other foot parallel to the screw member and having sliding engagement with the transerrer arm and cooperating with the screw member to prevent angular movement of said other foot relative to the transerrer arm.

5. In a transerrer arm for a reserve bobbin having a butt and a tip, a foot on the transerrer arm to engage the butt of the bobbin, spaced webs fixed with respect to and extending laterally from said foot, another foot to engage the tip end of the bobbin, parallel members, one for each web, extending into the latter and supporting said other foot, one of said members being capable of varying the distance of said other foot from the first named foot, and the other member being slidable in the corresponding web and cooperating with said one member to prevent angular movement of said other foot relative to the first named foot.

6. In a transerrer arm for a reserve bobbin having a butt and a tip, a foot on the transerrer arm to engage the butt of the bobbin, spaced

webs fixed with respect to and extending laterally from said foot, another foot to engage the tip end of the bobbin, parallel members, one for each web, extending into the latter and supporting said other foot, one of said members being screw threaded into the corresponding web and effective when rotated to vary the distance between said feet, and the other member being slidable in the web associated therewith when the distance between said feet is varied, said other member cooperating with the first named member to prevent relative angular movement of said feet.
